Primary Examiner — Dana K Weiland*Assistant Examiner* — Jenny lou M Binas(74) Attorney, Agent, or Firm — Wayne IP LLC(57) CLAIM

The ornamental design for a hand-held vacuum cleaner, as shown and described.

DESCRIPTION

FIG. 1 is a perspective view of hand-held vacuum cleaner showing my new design;

FIG. 2 is a front elevation view thereof;

FIG. 3 is a back elevation view thereof;

FIG. 4 is a left side view thereof;

FIG. 5 is a right side view thereof;

FIG. 6 is an enlarged top plan view thereof;

FIG. 7 is an enlarged bottom plan view thereof; and,

FIG. 8 is an enlarged view of the hand-held vacuum cleaner shown within the area designated as 8 in FIG. 4.

The broken ones in the drawings illustrate portions of the hand-held vacuum cleaner and form no part of the claimed design. The dashed broken line in FIG. 8 shows the boundary of the enlarged view and forms no part of the claimed design.
